REINFORCED SOAP CAKE

John Stone Stone, San Diego, Calif.

Application May 31, 1933, Serial No. 673,614

1 Claim. (Cl. 87—23)

The invention relates to an improvement in the art of soap manufacture and more specifically to soap which is formed and dispensed in oblong cakes.

5 An oblong cake of soap is extremely convenient, particularly for toilet and bath purposes, but in the use thereof the serious disadvantage results that, after three-quarters or four-fifths of the cake has been consumed, the thin remaining 10 oblong cake breaks in two and these two remnants of the cake lack all the conveniences possessed by the original cake.

15 Various ways of making secondary uses of these soap remnants may be adopted as measures of economy, but none of these is truly economical since the remnants must then be made to serve purposes more conveniently performed by the cheaper soap powders or liquid soaps.

20 Impartial experiments show that in the case of one of the most widely used cake soaps, the cake breaks in two by the time it is only three-fourths used. Thus the wasteful or inconvenient soap remnants in this case contain 25% of the soap the purchaser originally paid for.

25 The object of my invention is to provide a soap cake in the use of which these wasteful, annoying and inconvenient soap remnants are not produced.

30 Another object of my invention is to provide an oblong soap cake, so constructed and composed that its purchaser may have the use, in cake form, of all the soap he pays for.

35 A further object of my invention is to provide a soap cake, oblong or otherwise, containing a talisman redeemable in trade by the purchaser.

40 A still further object of my invention is to provide an oblong soap cake fortified or strengthened at its core so that it will not tend to break into pieces after partial use.

45 Yet another object of the invention is to shape the buoyant, cake-reinforcing core in an improved manner thereby to effect a more complete and certain economizing of the soap.

50 These several objects are attained through the formation of an oblong soap cake about a central core of a material mechanically stronger than the soap used in forming the cake. This core may be made of any material that is mechanically stronger than the soap which constitutes the cake, but when economy is the motive in using the invention, the core material must also be cheaper than the soap, while when the object in using the invention is such as that of 55 providing a talisman within the soap cake, beauty

of color or design may be added to its relatively greater mechanical strength.

Thus when economy only is the object, an oblong core of wood, cement, of wine bottle glass, or of like cheap material may be used, while when the relatively strong oblong core is to serve as a talisman, ornamental celluloid or like decorative material may be used in its construction.

When cement is used for the core, or wood of a porous or spongy character, an advantage results in that an improved bond is secured between the surface of the core and the adjacent part of the cake by compressing the cake so as to partially extend a portion thereof into the external portion of the core, thus leaving the remaining 15 portion of the pores unoccupied so as to provide air space to add buoyancy to the cake as a whole.

20 In some instances it may be found expedient to impregnate the core when it consists of a woody porous nature with perfume and permit the perfume to permeate the detergent surrounding the core. Thus several different kinds of perfumed cleansers may be had at one making.

25 Even when it is desired to have the core ornamental, such inexpensive material as cement may be used, but in such cases the core will be suitably stained or painted. Cement cores are preferably covered with a layer of paint to enhance their smoothness to the touch. The core 30 is preferably given a markedly distinctive color in order that it may not be confused with the soap which constitutes the soap cake.

The invention will be best understood by referring to the accompanying drawing illustrating the use of a relatively strong oblong core at the centre of a cake of soap wherein—

35 Fig. 1 is a perspective view of a cake of soap, a corner portion of the cake being broken away to disclose a part of the core provided with the invention.

40 Fig. 2 is a cross section taken on line 2—3 of Fig. 1.

45 Fig. 3 is a cross section showing another form of core.

So far as the soap portion of the article is concerned, for Fig. 3, the plan of section is on line 2—3 of Fig. 1.

50 Referring in detail to the drawing, the oblong soap body 4 may be of the conventional character as shown in Fig. 1. As shown in Figs. 1 and 2, a hollow core 5 is embedded in the central portion of the cake, said core being of greater length than width and extending longitudinally of the cake. This core is made sufficiently strong to 55

reenforce the cake and safeguard against break-
age after a considerable portion of the cake has
been consumed.

The core is shown of greatest thickness at its
5 mid-length and is tapered to relatively thin edge
portions 6. Said core may be constructed of
celluloid or other suitable material. It is pro-
vided with an interior hollow space 7, sufficiently
large to insure buoyancy for the cake as a whole.

10 In Fig. 3 is shown another kind of core 5a
which though it may be shaped the same as the
core 5, is made of porous wood and is therefore
buoyant like the core 5 although not provided
with a distinct internal air space.

15 The soap enters the end portions of the pores
8 and thus a suitable bond is furnished to cause
the soap to adhere to the core.

The internal portions of the pores provide air
spaces which add to the buoyancy of the cake.

20 The adhesive bond thus provided between the
core and the soap prevents the latter from break-
ing up into fragments even when nearly all the
soap has been consumed on the core.

The core 5a is not only provided with the pores
25 8 but is also furnished with a roughened surface
which causes the soap to adhere more firmly to
its surface.

Both the kinds of cores shown may be used as
talisman after the soap has been used up.

30 Both forms of core are of a flattened charac-

ter and are surrounded by edge portions which
taper uniformly to approximately an acute an-
gle, thus insuring that no unused streak of soap
will remain around the thinned portion of the
core.

5 In either case the soap is gradually dissolved
away until the fortifying core is all that is left.
This core is then discarded without compunction
by the user of the soap, unless the fortifying core
be designed as a talisman entitling its owner to 10
redeem it in trade, in which case, it is saved and
a collection of such cores made until the number
secured is great enough to entitle the possessor
to a privileged trade.

Or the core 5 or 5a may be made of a deter- 15
gent possessing the cleansing qualities of the
body 4. In the later event the core would be
constructed more firmly, as for example like
castile soap, and would be of less solubility than
the remaining portion of the cake.

20 I claim:

A cake of soap having embedded therein a
porous buoyant reenforcing core, said core hav-
ing transverse non-communicating passageways
extending from one extremity to the other, the 25
extremities of each passageway containing por-
tions of the soap which forms seals for entrap-
ping the air in the intermediate spaces and thus
add to the buoyancy of the soap as a whole.
